HOT AND COLD AIR BASEBOARD REGISTER

Zeno F. Molitor, Stockton, Ill.

Application May 24, 1957, Serial No. 661,479

3 Claims. (Cl. 98—40)

This invention relates to a novel combination hot and cold air baseboard register capable of functioning for extracting cold air from adjacent the floor of an enclosure and for discharging hot air upwardly into the enclosure.

More particularly, it is an aim of the present invention to provide a combination hot and cold air register which is extensible and retractable and adapted for fitting hot and cold air ducts which are spaced different distances apart, and which register is horizontally divided into an upper hot air chamber into which a hot air duct may discharge and a lower cold air chamber which may be connected to and communicate with a cold air return duct.

Still a further object of the invention is to provide a baseboard register formed of extensible sections whereby the length of the register may be adjusted to fit hot and cold air ducts spaced different distances apart.

Various other objects and advantages of the invention will hereinafter become more fully apparent from the following description of the drawings, illustrating a presently preferred embodiment thereof, and wherein:

Figure 1 is a fragmentary front elevational view of the combination hot and cold air baseboard register;

Figures 2 and 3 are enlarged transverse vertical sectional views, taken substantially along planes as indicated by the lines 2—2 and 3—3, respectively, of Figure 1;

Figure 4 is a fragmentary horizontal sectional view, taken substantially along a plane as indicated by the line 4—4 of Figure 1, and

Figure 5 is a fragmentary vertical sectional view of the register, taken substantially along a plane as indicated by the line 5—5 of Figure 4.

Referring more specifically to the drawings, the combination hot and cold air baseboard register in its entirety is designated generally 7 and is composed of an intermediate section, designated generally 8, and end sections designated generally 9 and 10. Each of the register sections is formed of sheet metal.

The intermediate section 8 is composed of two strips of sheet metal one of which strips forms the rear part of the register section 8 and which includes a rear wall 11, a horizontal partition wall 12, a bottom wall 13 and a front flange 14. The partition wall 12, which is disposed above and spaced from the bottom 13, constitutes a forwardly extending lapped two-ply portion of the rear wall 11. The parts 11, 12, 13 and 14 extend from end-to-end of the intermediate section 8. A second elongated piece of sheet metal forms the front and top of the register section 8 and is of the same length as the piece forming the parts 11 to 14 and includes a lower portion forming the front wall 15 of the register section 8. A bottom longitudinal edge portion of the front wall 15 bears against and is suitably secured as by welding, as seen at 16, to the outer side of the upturned flange 14. The front part of the register section 8 includes an inclined top wall 17 which extends upwardly and rearwardly at

2

an incline from the upper edge of the front wall 15 and has a downturned flange 18 at the upper edge thereof which bears against the outer side of the upper portion of the rear wall 11. The parts 15, 17 and 18, all of which are formed from the second strip of metal, each extends from end-to-end of the register section 8. The upper portion of the front wall 15 is provided with a plurality of struck-out portions forming openings 19 and externally disposed upwardly opening louvers 20, which communicate with said openings 19 and which open upwardly and outwardly of the register 7. The louvers 20 and openings 19 are disposed in vertically spaced apart relation to one another, as seen in Figures 1 and 3, and said front wall 15 may be provided with a plurality of longitudinally spaced sets of said openings and louvers, depending upon the length thereof. The lower portion of the front wall 15 is also provided with struck-out portions forming openings 21 and louvers 22, corresponding to the openings 19 and louvers 20, except that the lower louvers 22 open downwardly instead of upwardly, as clearly illustrated in Figure 3. The openings 19 and louvers 20 are disposed above the level of the partition wall 12, and the openings 21 and louvers 22 are disposed below the level of said partition wall. The open ends of the intermediate section 8 are closed by the end sections 9 and 10 which telescopically engage over said open ends, and which may be extended or retracted to vary the over-all length of the register 7. Each end section 9 and 10, as best illustrated in Figures 2, 4 and 5, includes a substantially flat upright rear wall 23, an outer end wall 24 and a front flange 25, which parts are formed from a single piece of sheet metal. The end wall 24 is disposed at right angles to the rear wall 23 and flange 25, and said rear wall and flange extend in the same direction from the end wall 24. The end wall 24 has an inclined upper edge 26, the lower end of which is disposed above the level of the upper end of the front flange 25. Each end section 9 and 10 also includes an upright front wall 27, an inclined top wall 28 and a flange 29 forming a downturned extension of the upper edge of the top wall 28 and which engages the upper portion of the outer side of the rear wall 23. The parts 27, 28 and 29 are formed from a single piece of sheet metal and the outer end of the inclined top wall 28 bears against the inclined upper edge 26 of the end wall 24. The outer edge of the front wall 27 bears against the outer side of the front flange 25 and is secured thereto, as by welding, as seen at 30. Each end section 9 and 10 also includes an upper partition 31 and a lower partition 32, each of which is formed from a strip of sheet metal. The partitions 31 and 32 have complementary upturned ends 33 and 34, respectively, which are disposed against the inner side of the end wall 24 and which are secured thereto, as by additional welds 35. The partitions 31 and 32 extend to the inner open end of the end section and are of a width less than the spacing between the rear wall 23 and front wall 27 and have their side edges spaced slightly from said walls. Said partitions 31 and 32 are offset upwardly slightly relative to the partition 12 and bottom 13 of the intermediate section 8, respectively, so as to slidably engage thereover when the end sections 9 and 10 are telescoped onto the ends of the intermediate section 8. Said partitions 31 and 32 are preferably provided with upturned tabs 36 at their inner ends which bear against the inner side of the front wall 15, as best seen in Figures 3 and 4. The spacing between the front wall 27 and the rear wall 28 is slightly greater than the spacing between the walls 15 and 11, and the height of the rear wall 23 of each end section is slightly greater than the height of the rear wall 11, so that the end sec-

tions 9 and 10 are sized to fit over the ends of the intermediate section 8.

The assembled register 7, as seen in Figure 1, is adapted to rest on a floor 37 and with the upright back side of the register disposed against the lower portion of an upright wall 38, in the same manner that a baseboard is secured to the corner formed by a floor and wall. The end sections 9 and 10 are extended or retracted to locate one end section over the discharge end of a hot air duct 39, which extends upwardly through the floor 37, adjacent the wall 38, and to locate the other end section directly over the open inlet end of a cold air duct 40, which also extends upwardly through the floor 37, adjacent the wall 38. As illustrated in Figures 2 to 5, the end section 9 is located in vertical alignment with the hot air duct 39. The partitions 31 and 32 thereof are provided with "knockouts" which are removed to form openings 31' and 32', respectively, therein through which the upper portion of the hot air duct 39 extends, so that the discharge end of the hot air duct opens above and adjacent the partition 31 of the end section 9. The knockout of the bottom partition 32 only of the other end section 10 is removed to provide an opening 32' through which the upper portion of the cold air duct 40 extends and so that the inlet end of said cold air duct is located immediately above said lower partition 32 of the section 10. The knockout 41 of the upper partition 31 of the section 10 is not removed so that the chamber 42 of the register 7, which is disposed above the partitions 12 and 31, is closed off from the lower chamber 43, which is disposed beneath said partitions 12 and 31. Said chambers 42 and 43 extend from end-to-end of the register 7. If the ducts 39 and 40 are sufficiently large in size so as to substantially correspond to the spacing between the rear walls 23 and front walls 27, the partitions 31 and 32 of the end section 9 could be removed entirely to accommodate the hot air duct 39 and the lower partition 32 of the end section 10 could be entirely removed to accommodate the inlet end of the cold air duct 40.

Assuming that the register 7 is assembled and positioned as illustrated in the drawings relative to the floor 37 and wall 38 and connected to the hot air duct 39 and cold air duct 40 as previously described and as illustrated, hot air from a heating system, not shown, would be supplied under pressure through the hot air duct 39 and will be discharged therefrom into the upper register chamber 42 from which the air will escape into the enclosure or room, of which the floor 37 and wall 38 form parts, through the openings 19 and the upwardly opening louvers 20. The hot air will thus be discharged upwardly away from the floor. At the same time, a suction will be created in the cold air duct 40 and, in turn, in the lower cold air chamber 43 of the register 7, so that cold air, adjacent the floor, will be drawn upwardly into the downwardly open louvers 22 and will enter the cold air chamber 43 through the openings 21 and will be withdrawn from the register through the cold air duct 40.

It will thus be apparent that the combination hot and cold air baseboard register 7 is adapted to be connected to both a hot air duct and a cold return duct for simultaneously supplying hot air to an enclosure and for extracting cold air therefrom.

Various modifications and changes are contemplated and may be resorted to, without departing from the function or scope of the invention as hereinafter defined by the appended claims.

I claim as my invention:

1. A hot and cold air baseboard register comprising an elongated hollow sheet metal casing having a bottom adapted to rest on a floor and an upstanding rear wall adapted to be disposed against a wall, said casing including a front wall having an upper set and a lower set of elongated openings each extending longitudinally of the casing, a louver associated with each of said openings, 75

said louvers being struck outwardly from said front wall, and said openings opening outwardly of the casing into the louvers, the louvers, associated with the upper set of openings, being disposed to open upwardly, and the louvers, associated with the lower set of openings, being disposed to open downwardly, said casing having an elongated partition extending from end-to-end thereof, said partition being disposed between the upper and lower sets of openings and dividing said casing into a lower return air chamber disposed below the partition and an upper hot air chamber disposed above the partition, and said casing having means adapted to accommodate the discharge end of a hot air conduit to discharge into said upper chamber and a second means for accommodating an inlet end of a return air conduit in communication with said lower chamber, said casing including an intermediate section having open ends and end sections having open inner ends and closed outer ends, the open inner ends of said end sections telescopically engaging the open ends of said intermediate section, and said partition including end portions carried by said end sections and telescopically engaging an intermediate partition portion carried by said intermediate section, said openings and louvers being formed in the front wall portion of said intermediate section, said end sections being extensible and retractable to vary the over-all length of the register to accommodate the register to the spacing between the hot and return air ducts, the bottom and partition portion of one of said end sections being provided with said means for accommodating the discharge end of the hot air conduit which extends upwardly therethrough, and the bottom portion of said other end section being provided with said means for accommodating the inlet end of the return air duct which extends downwardly therefrom through the floor.

2. A hot and cold air baseboard register as in claim 1, said casing having an inclined top wall extending upwardly and rearwardly from said front wall and connected to the upper edge of the rear wall.

3. A baseboard register comprising an elongated sheet metal casing adapted to rest on a floor and having a rear wall adapted to be disposed against a portion of a wall, said casing including an intermediate section and end sections, said end sections telescopically engaging the ends of said intermediate section for varying the length of said casing, a partition dividing said casing from end-to-end thereof into a lower return air chamber and an upper supply air chamber, said partition including end portions carried by said end sections and telescopically engaging an intermediate partition portion carried by said intermediate section, the bottom and partition portion of one of said end sections having means adapted for receiving a discharge end of an air supply duct and for positioning the outlet end of said supply duct in communication with said upper air chamber, the bottom of said other end section having means adapted to accommodate a return air duct for positioning an open inlet end thereof in communication with said lower return air chamber, said intermediate section including a front wall having openings disposed above said partition and communicating with the supply air chamber for the escape of air therefrom and other openings communicating with said return air chamber for admitting air to said lower chamber.
